1 Claim

ABSTRACT OF THE DISCLOSURE

A device for flushing an automobile radiator at its normal operating pressure and temperature including means for introducing makeup cooling liquid, a regulator valve for adjusting the flow of makeup liquid, a pressure indicator to indicate the pressure of makeup liquid and a pressure relief radiator closure adapted to vent the system at pressures above its normal operating pressure.

The present invention pertains to flushing devices, and more particularly, to devices of the type particularly adapted to be connected to an automotive radiator for flushing the automotive cooling system.

It is frequently necessary to flush an automotive cooling system to remove accumulated rust or foreign matter to thereby restore the efficiency of the system. Prior art devices have been suggested for accomplishing this feat ranging from the simple utilization of a hose placed in the radiator filler opening to complicated devices using gauges, valves, and a variety of indicators.

When flushing an automotive radiator, it is important for the system to be operating under full capacity; full-capacity operation requires that any thermostat connected in the cooling system fluid or liquid path be opened. Using prior art techniques for flushing automotive cooling systems, cold water is continuously presented to the thermostat, thus restricting the flow of liquid through the engine and thereby militating against the efficient flushing thereof. Further, the flushing efficiency is reduced by running liquid through the cooling system under substantially reduced pressure since the system is left open both at the drain cock of the radiator and the radiator filler opening.

It is therefore an object of the present invention to provide an automotive cooling system flushing device that provides flushing liquid throughout the cooling system, said liquid being at normal operating temperatures.

It is another object of the present invention to provide an automotive cooling system flushing device wherein the liquid being circulated throughout the cooling system is at normal operating temperatures.

It is still another object of the present invention to provide an automotive cooling system flushing device that permits the flow regulation through the cooling system during the flushing operation to maintain normal operating conditions throughout the system to thereby efficiently flush the same.

The present invention may more readily be described by reference to the accompanying drawings in which:

FIGURE 1 is a perspective view of an automotive cooling system flushing device constructed in accordance with the teachings of the present invention.

FIGURE 2 is a cross-sectional view of FIGURE 1 taken along line 2—2.

Referring to the drawings, a portion of an automotive radiator is shown at 10 and includes a radiator filler opening 11 to permit addition of liquid therethrough. A neck 12 extends upwardly from around the filler opening to permit the fastening of a conventional radiator cap thereto. The device of the present invention includes

2

a radiator filler opening closure 13 adapted to fit over the flange 14 of the neck 12. The fastener of the closure is similar to the fastening of a conventional radiator cap; a pressure-relief mechanism including a coil spring 15, a shoe 16, and a gasket 17 are included and form an efficient seal to prevent the escape of liquid therefrom. In the event that the pressure within the cooling system exceeds the pressure for which the coil spring was designed, the shoe 16 is moved upwardly to compress the spring 15 to thereby permit the escape of liquid and steam to the chamber within the neck 12 and through a drain opening 20 provided therein. The pressure-relief radiator closure including the coil spring and shoe mechanism, as well as the cap 13, is connected to a valve body 25 having a passageway 26 therein communicating to the radiator filler opening 11. The regulator valve includes a manually operable valve 27 connected to a valve stem 28 and threadably positionable with a predetermined distance of the valve seat 29.

20 The valve stem may be turned by turning the knurled disc 31 to thereby lower or raise the valve in accordance with the desired flow.

The passageway 26 is also connected through appropriate fittings 32 to a pressure indicator 35. The indicator 25 may be calibrated in appropriate units—usually in an appropriate range of pounds per square inch suitable for covering the range of normal automotive cooling system pressures. Means for connecting the valve to a source of liquid under pressure may take the form of a simple hose 30 connector 40 rotatably connected to a threaded stud 41, the latter extending into the valve body. In this manner, a hose 45, or other suitable source of liquid under pressure, may conveniently be connected to the regulator valve.

35 The operation of the automotive cooling system flushing device of the present invention may now be described. When an automotive cooling system is to be flushed, the drain cock on the radiator is opened, and the radiator cap is removed. The flushing device of the present invention is placed on the radiator filler opening to thereby seal the opening in a manner similar to the seal 40 formed by the cap. The source of liquid under pressure is applied to the regulator valve, and the engine is started. Liquid is thus supplied through the regulator 45 valve through the pressure-relief radiator closure into the radiator and thus through the engine cooling system. The engine, which has been running, heats the liquid thus actuating the thermostat and permitting the liquid to flow through the engine block. The pressure of the 50 system is regulated by adjusting the regulator valve and observing the pressure on the pressure indicator. The pressure is adjusted to the pressure of normal operation for the particular engine being flushed. In this manner, the engine is used to heat the water in a normal fashion to thereby operate the thermostat and permit full liquid flow throughout the cooling system. Further, the system is operated under normal operating pressures to provide more complete access to all the interstices of the engine 55 cooling passageways in a more thorough cleansing action. The device of the present invention permits the flushing of the automotive cooling system under the proper pressure and temperature conditions without necessitating expensive or complicated apparatus; the device is compact and unitary and conveniently attached to the standard radiator filler openings.

60 It will be obvious to those skilled in the art that the present invention has been described in terms of a specific embodiment; therefore, it is intended that the present embodiment not limit the scope of the invention and that the invention be limited only by the scope of the 65 claims appended hereto.

70

1 claim:

1. An automotive cooling system flushing device for flushing an automotive cooling system at its normal operating temperature and pressure comprising: a pressure-relief radiator closure adapted to fit over a radiator filler opening, said closure including a passageway therethrough for introducing makeup cooling liquid into said system and being preset to vent said system when the pressure therein substantially exceeds the normal operating pressure of said system; a regulator valve communicating with said passageway and having means for adjusting the flow of makeup cooling liquid therethrough; a pressure indicator connected to indicate the pressure of the liquid in said passageway; and means for connecting said valve to a source of makeup cooling liquid under pressure.
